US0D1081542S

(12) **United States Design Patent** (10) **Patent No.:** **US D1,081,542 S**
(45) **Date of Patent:** **** Jul. 1, 2025**

(54) **BATTERY HOUSING**

(71) Applicant: **Shenzhen Ampere Time Digital Energy Technology Co., Ltd., Shenzhen (CN)**

(72) Inventors: **Zhiyong Hu**, Chibi (CN); **Haijun Lu**, Shenzhen (CN)

(73) Assignee: **Shenzhen Ampere Time Digital Energy Technology Co., Ltd., Shenzhen (CN)**

(**) Term: **15 Years**

(21) Appl. No.: **29/978,431**

(22) Filed: **Dec. 12, 2024**

(30) **Foreign Application Priority Data**

Nov. 19, 2024 (CN) 202430732085.7

(57) **CLAIM**

The ornamental design for a battery housing, as shown and described.

DESCRIPTION

FIG. 1 is a bottom front perspective view of a battery housing showing our new design;

FIG. 2 is a top rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

1 Claim, 8 Drawing Sheets
